PUMP OR FLUID MOTOR OF THE GEAR TYPE

Bruce H. Mosbacher, Rockford, Ill., assignor to Geo. D. Roper Corporation, Rockford, Ill., a corporation of Illinois

Application June 1, 1953, Serial No. 358,625

14 Claims. (Cl. 103—117)

This invention relates to a novel pump or fluid motor of the type which employs a plurality of rotary gears for displacing the fluid.

It is an object of this invention to provide a novel and improved pump or fluid motor of the type having rotary gears in the fluid displacement mechanism.

It is also an object of this invention to provide a novel pump or fluid motor of this general type which is adapted for pumping water, abrasive liquids and other fluids which conventional gear pumps have been found to be impractical to handle.

Another object of this invention is to provide a novel pump or fluid motor of the gear type having reduced wear on the moving parts due to the absence of metal-to-metal contact therat.

Another object of this invention is to provide a novel pump or fluid motor of the gear type which is quieter in operation than conventional devices of this type.

An additional object of this invention is to provide a pump or fluid motor of the gear type of novel construction in which the drive load is distributed across the periphery of the gears and which avoids concentrating the drive load at line contact between the gears, as is the case in conventional gear pumps.

A further object of this invention is to provide a pump or fluid motor of the gear type which is of novel construction enabling the use of soft plastic gears in the fluid displacement mechanism, thereby reducing the cost of the device as compared with devices of this type which require metal gears.

A still further object of this invention is to provide a novel pump or fluid motor of the gear type having twice the fluid displacement for a given tooth depth of conventional gear pumps of fluid motors.

Yet another object of this invention is to provide a pump or fluid motor of the gear type which is of novel construction in which the bearing loads are lessened because of the reduced projected areas of the gears exposed to the fluid under high pressure.

Also, it is an object of this invention to provide a novel pump or fluid motor of the gear type in which all of the gears turn in the same direction.

The foregoing objects and advantages of the present invention are preferably accomplished by mechanism which includes a plurality of spaced rotary gears, an endless flexible toothed belt extending around the gears in driving relation therewith, and spaced low pressure and high pressure passages communicating with the inter-tooth spaces on the gears and the belt for the displacement of fluid as the gears rotate and the belt turns therewith.

Other and further objects and advantages of the present invention will be apparent from the following description of several preferred embodiments thereof, shown in the accompanying drawings.

In the drawings:

Figure 1 is an axial sectional view of a first, two-gear

embodiment of the present invention, taken along the line 1—1 in Fig. 2;

Figure 2 is a longitudinal section through the Fig. 1 device, taken along the line 2—2 in Fig. 1;

5 Figure 3 is a longitudinal sectional view of a second, four-gear embodiment of the present invention;

Figure 4 is a longitudinal sectional view of a third, three-gear embodiment of the present invention; and

10 Figure 5 is a longitudinal sectional view of a fourth, multiple-gear embodiment of the present invention wherein the belt meshes with gears at both its inner and outer faces.

Referring to the first embodiment of the invention, shown in Figs. 1 and 2, the pump or motor includes a

15 spaced pair of spur gears 10 and 11 which are of conventional design, having gear teeth entirely around their respective peripheries. The gears are out of meshing relationship with one another, being separated by a fixed spacer plate 12, which has arcuate end faces 13 and 14 providing close running fits for the mutually adjacent, inwardly facing peripheral portions of the gears. An endless flexible belt 15 extends around the gears and the spacer plate. This belt is formed at its inner face with teeth or lugs 16 which mesh closely with the teeth on the gears, as best seen in Fig. 2, so that the belt is in driving relation with both gears. Between the gears the spacer plate 12 presents opposite flat end faces 17, 18 which provide close running clearances for the toothed inner face of the belt thereat.

20 30 The endless flexible belt 15 is preferably of the type known as the "Gilmer timing belt," which has come into extensive use as a power transmission medium where a non-slip power transmission or precise synchronization between two or more rotary shafts is required. This belt is preferably of cabled steel wire embedded in neoprene at the outer side of the belt, a plurality of spaced, relatively hard, neoprene teeth at the inner side of the belt, and a neoprene-impregnated fabric layer serving as a facing for the inner face of the belt.

35 40 The entire assembly of the gears 10, 11, spacer plate 12, and belt 15 is enclosed within a housing (Fig. 1) consisting of the spaced end plates 19 and 20, and the intermediate casing member 21 clamped between the end plates, with resilient gaskets 22, 23 interposed therebetween.

45 50 As shown, the gasket 23 provides a close running clearance for the gears at one end face thereof, while at the opposite end faces of the gears the intermediate casing member 21 is formed with a transverse shoulder 24, which provides close running fits for the gears thereat. Between its shoulder 24 and the gasket 23 the intermediate casing member 21 defines an oblong chamber 25 of the configuration indicated in Fig. 2. The smooth outer face of the timing belt 15 has a close running fit in this chamber substantially completely around 55 the belt, as indicated in Fig. 2.

55 60 Referring to Fig. 1, the gear 10 carries an integral journal 10a which is rotatably received in a passage 26 formed in the intermediate casing member 21 extending from the internal shoulder 24 thereon to the gasket 22. At its opposite end the gear 10 carries an integral journal 10b rotatably supported by a cylindrical bearing bushing 27, which is snugly received within a cylindrical cavity 28 in the end plate 20 extending outwardly from the gasket 23. The gear 11 carries integral journals 11a

65 70 and 11b at its opposite ends which are supported for rotation by bearing sleeves 29 and 30 disposed respectively in cavities 31 and 32 in the intermediate end housing members 21 and 20, respectively.

70 For introducing fluid into the chamber 25, when the device is operated as a pump, the intermediate casing member 21 is formed with a threaded inlet passage 33 which leads to a low pressure passage 34 extending com-

pletely across the housing chamber 25. As shown in Fig. 2, the passage 34 communicates with the space between the gear 11, the toothed inner face of the belt 15 and the upper right corner of the spacer plate 12 in Fig. 2, immediately adjacent the location where the belt engages the gear 11. The passage 34 also extends across the outer face of the belt here; otherwise, fluid pressure unbalance on the opposite faces of the belt might force the belt too tightly against the wall of chamber 25. Alternatively, for this purpose the belt 15 might be formed with holes effecting communication between the opposite faces of the belt, so that the passage 34 would not have to extend across the outer face of the belt in order to balance the fluid pressures thereon.

The end wall of the intermediate casing member 21 is also formed with an internal passage 35, which extends from the passage 34 around to a passage 36 communicating with the space between the gear 10, the toothed inner face of belt 15 and the lower left corner of spacer plate 12 in Fig. 2, immediately adjacent the engagement of the belt with this gear. Passage 36 also communicates with the outer face of the belt entirely thereacross to balance the pressures on the opposite faces of the belt at this location.

A threaded discharge passage 37 formed in the intermediate casing member 21 leads to high pressure passages 38 and 39 in chamber 25 which are interconnected by an internal passage 40 formed in the end plate 20. The passage 38 communicates completely across the belt with the space between the gear 11, the belt 15 and the lower right corner of the spacer plate in Fig. 2, as well as across the outer face of the belt thereat. Likewise, the high pressure passage 39 communicates completely across the belt with the space between the gear 10, the belt and the upper left corner of the spacer plate 12 in Fig. 2, as well as across the outer face of the belt at this location for pressure balancing purposes.

In the operation of this device, assuming that it is being operated as a pump, the gear 10 is driven through a connection from a suitable prime mover (not shown), such as an electric motor, to the drive shaft 41. The drive shaft is suitably connected to the gear journal 10a and is supported for rotation on the housing by a conventional ball bearing assembly 42. A seal 43 extends around the drive shaft to prevent leakage out of the housing along the drive shaft.

Assuming that the drive shaft rotates gear 10 counterclockwise in Fig. 2, this gear will drive the belt 15 counterclockwise, and the belt in turn will drive the other gear 11 in the same direction. Fluid drawn in through the low pressure passage 34 passes to the spaces between the teeth on gear 11 and to the spaces between the belt teeth thereat. As the gear 11 turns counterclockwise, the fluid in its intertooth spaces is carried around past the end face 14 of the spacer plate 12 to the high pressure discharge passage 38. The close running fit of the gear 11 at the arcuate end face 14 of the spacer plate 12 causes the fluid to be trapped in these intertooth spaces on gear 11 and carried around to the discharge passage 38 in this manner. The remainder of the fluid entering at the low pressure passage 34 is trapped in the intertooth spaces on belt 15 between the belt and the end face 17 of the spacer plate and is carried around to the high pressure discharge passage 39 as the belt moves counterclockwise.

In like manner, a portion of the fluid entering at the low pressure passage 36 is carried by gear 10 around to the high pressure discharge passage 39, while the remainder of this fluid is carried by the belt 15 over to the other high pressure discharge passage 38.

It will be noted that with this arrangement there is no engagement between the gears, the driving connection between the gears being effected by the belt, which results in much quieter operation and reduced wear. For this reason, if desired, the gears may be made of soft plastic or other material besides metal. Also, the avoidance of

contact between the gears enables the pump to be employed for pumping fluids containing abrasives and the like, which is not feasible in conventional gear pumps because of the resultant undue wear on the gears.

Whereas in conventional gear pumps, the entire drive load is concentrated at the substantially line contact between the gears, in the device described above the drive load is spread out across approximately one-half the circumference of each of the gears where the endless belt is in driving engagement with the gears.

Also, since approximately half the fluid pumped is carried in the intertooth spaces on the belt, the capacity of the pump is effectively double the capacity of a conventional gear pump having gears of the same tooth depth and operating at the same speed.

From Fig. 2, it will be observed that only a relatively small peripheral area of each of the gears 10 and 11 is exposed to the high pressure fluid at the passages 38 and 39, so that the resultant unbalance thrusts on these gears is minimized proportionately. Therefore, the bearing loads on these gears are less than in conventional gear pumps, where greater peripheral areas of the gears are exposed to the fluid under high pressure.

In the second embodiment of the present invention, illustrated in Fig. 3, there are provided four spaced spur gears 50-53 arranged in a square pattern. A fixed spacer block 54 separates the gears from one another and is formed with a first substantially semi-circular face 55 providing a close running clearance for the inwardly disposed portion of the toothed periphery of gear 50, a second substantially semi-circular face 56 providing a close running clearance for the inner toothed peripheral portion of gear 51, a third substantially semi-circular face 57 providing a close running fit for the inwardly disposed portion of the toothed periphery of gear 52, and a fourth substantially semi-circular face 58 providing a close running fit for the inner portion of the periphery of gear 53.

An endless flexible belt 59 of the type described in detail above extends around the gear and spacer assembly and has teeth at its inner face which mesh with the gear teeth on each of the gears. The spacer block 54 presents flat and faces 60-63 located respectively between the gears and providing close running clearances for the toothed inner face of the endless belt thereat. The endless belt 59 has a close running fit at its smooth outer face in the chamber 64 formed in the housing 65.

Within the housing there are provided a plurality of low pressure passages 66-69, which communicate respectively with the spaces between the toothed inner face of the endless belt, the spacer block and the gears immediately adjacent where the belt meshes with the gears. In similar fashion, the high pressure passages 70-73 communicate respectively with the spaces between the toothed inner face of the endless belt, the spacer block and the gears, immediately adjacent the opposite end of the engagement of the belt with the respective gear. As in the first described embodiment of the invention, the high and low pressure passages are arranged in alternate sequence along the belt. At each of the high and low pressure passages the outer face of the endless belt is exposed to the fluid thereat, so as to balance the fluid pressures on the opposite faces of the belt at these locations.

In the operation of the Fig. 3 device as a pump, with all of the gears and the endless belt moving clockwise, fluid drawn in at the low pressure inlet 66 is carried by gear 50 around to the high pressure outlet 73 and by the endless belt over to the high pressure outlet 70, fluid entering at the suction inlet 67 is carried by gear 51 around to the high pressure outlet 70 and by the belt to the high pressure outlet 71, fluid drawn in at the suction inlet 68 is carried by gear 52 around to the high pressure outlet 71 and by the belt over to the high pressure outlet 72, and fluid drawn in at the suction inlet 69 is carried by gear 53 around to the high pressure outlet 72 and by the belt over to the high pressure outlet 73. In

this operation, the close running clearances provided for the gears by the arcuate faces 55-58 on the spacer cause the fluid to be trapped in the intertooth spaces on the respective gears, while the close running fits provided for the toothed inner face of the endless belt by the flat end faces 60-63 cause the fluid to be trapped in the intertooth spaces on the belt and carried thereby between the gears from a suction inlet to the next high pressure outlet, as described.

In the third embodiment of the invention, shown in Fig. 3, there are provided three gears 80, 81, 82 having their respective axes of rotation disposed in one plane. A fixed spacer block 83 separates the end gear 80 from the larger, middle gear 81 and is formed with an arcuate end face 84 which provides a close running clearance for the inwardly disposed portion of the toothed periphery of gear 80, as well as an arcuate opposite end face 85 providing a close running clearance for a portion of the periphery of middle gear 81. A similar spacer block 86 separates the middle gear 81 from the other end gear 82, being formed with an arcuate end face 87 providing a close running fit for the inwardly disposed peripheral portion of gear 82 and an opposite arcuate end face 88 providing a close running fit for the adjacent portion of the periphery of middle gear 81.

An endless flexible belt 89 extends around the assembly of gears and is formed with teeth at its inner face meshing with the gear teeth. The spacer block 83 presents flat end faces 90 and 91 which provide close running clearances for the opposite courses of the belt 89 between the gears 80 and 81. Similarly, the other spacer block 86 presents flat end faces 92 and 93 providing close running clearances for the opposite courses of belt 89 between the gears 81 and 82. Due to the larger diameter of the middle gear 81, it imparts a slight tension to the belt 89, preventing the belt from slackening an undesired amount. At its smooth outer face the belt 89 has a close running clearance in the chamber 94 formed by the housing 95.

Within the housing there are provided a plurality of low pressure passages 96-99 communicating respectively with the spaces between the endless belt, the respective spacer blocks and the respective gears immediately adjacent the point of mesh of each gear with the belt. Also, there are provided the high pressure passages 100-103, which communicate respectively with the spaces between the endless belt, the respective spacer blocks and the respective gears at the opposite sides of the spacer blocks from the low pressure passages, immediately adjacent the engagement thereof of each gear with the belt. As is clear from Fig. 4, these low and high pressure passages are arranged in alternate sequence along the belt. The outer face of the endless belt is exposed to the fluid pressure at each of these passages, so that the fluid pressures are balanced on opposite faces of the belt at these locations.

In the operation of this embodiment of the present invention, assuming clockwise rotation of the gears and clockwise movement of the endless belt, and also assuming that the device is operated as a pump, fluid drawn in at the low pressure inlet passage 96 is carried by the gear 80 around to the high pressure outlet passage 103 and by the belt over to the high pressure outlet passage 100, fluid drawn in at the low pressure inlet passage 97 is carried by the gear 81 around to the high pressure outlet passage 102 and by the belt over to the high pressure outlet passage 101, fluid entering at the low pressure inlet passage 98 is carried by gear 82 around to the high pressure outlet passage 101 and by the endless belt over to the high pressure outlet passage 102, and fluid entering at the low pressure inlet passage 99 is carried by gear 81 around to the high pressure outlet passage 100 and by the endless belt over to the high pressure outlet passage 103. At this time, the close running clearance provided by the

arcuate end face 84 of spacer block 83 causes fluid to be trapped in the intertooth spaces of gear 80, the close running clearances provided by the arcuate end faces 85 and 88 of the spacer blocks 83 and 86 cause fluid to be trapped in the intertooth spaces on the middle gear 81 and carried from the low pressure passages to the high pressure passages, as described, and the close running clearance provided by the arcuate end face 87 of spacer block 86 causes the entrapment of fluid in the intertooth spaces on gear 82. In like manner, fluid is trapped in the intertooth spaces on the endless belt 89 due to the close running clearances provided for the toothed inner face of the belt by the flat end faces of the spacer blocks, for the transfer of fluid between the inlet and outlet passages in the manner outlined above.

In the final embodiment of the invention, shown in Fig. 5, the endless belt is formed with teeth at both its inner and outer faces and meshes at both of these faces with the gears for pumping fluid. Thus, as shown in Fig. 5, the two spaced inner gears 110 and 111 mesh with the toothed inner face of the flexible belt 112. The spacer block 113 separates these gears and has arcuate end faces 114, 115 providing close running clearances for these gears and flat end faces 116, 117 providing close running clearances for the toothed inner face of the endless belt 112, as in the first described embodiment of the present invention. Alternately arranged low pressure and high pressure passages 118, 119, 120 and 121 communicate with the respective spaces between each gear, the endless belt and the spacer block for passing fluid to and from the toothed peripheries of the gears 110 and 111 and the toothed inner face of the endless belt 112.

The housing 122 which encloses the assembly of the inner gears 110, 111 and the endless belt 112 also encloses an outer gear 123 positioned to mesh with the toothed outer face of the endless belt, so that this outer gear is driven by the belt. With the inner gears 110, 111 and the endless belt 112 all turning clockwise in Fig. 5, the endless belt drives the outer gear 123 in the opposite direction.

The housing 122 is formed with a bore 124 receiving the outer gear 123 and providing a close running fit therefor between the low pressure passage 125 and the high pressure passage 126. This bore 124 intersects the oblong chamber 127 in the housing 122 which provides a close running fit for the endless belt.

In the operation of this device, assuming pump operation, fluid drawn in at the low pressure inlet 118 is carried by gear 110 around to the high pressure outlet 121 and by the toothed inner face of endless belt 112 over to the high pressure outlet 119, fluid entering at the low pressure inlet 120 is carried by gear 111 around to the high pressure outlet 119 and by the toothed inner face of belt 112 over to the high pressure outlet 121, while fluid entering the low pressure inlet 125 is carried by gear 123 around to the high pressure outlet 126. Of course, a portion of the fluid entering at the low pressure inlet passage 125 is carried in the intertooth spaces on the outer face of the endless belt 112 around to the high pressure outlet passage 126.

It will be obvious that the principle of operation of the Fig. 5 device may be extended to include two or more outer gears, one such additional outer gear being shown in dotted lines in Fig. 5. Since the flexible endless belt forms the drive for the outer gears, any number of such outer gears which may be conveniently grouped about the outer face of the belt may be provided, as desired. Also, with such outer gear assembly any desired arrangement of the inner gears encircled by the endless belt may be provided, such as the four gear arrangement of Fig. 3 or the three gear arrangement of Fig. 4.

While in the foregoing description and in the accompanying drawings there have been disclosed several preferred embodiments of the present invention, it is to be understood that various modifications, omissions and re-

finements which depart from the disclosed forms of the invention may be adopted without departing from the spirit and scope of the present invention.

I claim:

1. A pump or fluid motor comprising spaced first and second rotary toothed gears, an endless flexible belt extending around said gears and formed at its inner face with spaced teeth received in the spaces between teeth on said gears, a housing enclosing said gears and said belt and having portions disposed in close running fit with the ends of said gears and belt, a spacer disposed between the spaced gears and formed with spaced arcuate opposite end faces extending respectively closely adjacent the toothed peripheral portions of the gears which are closest to one another and providing close running fits therat for said gears, said spacer being formed with spaced flat opposite end faces extending closely adjacent opposed portions of the toothed inner face of the belt between said gears, a first high pressure passage in the housing communicating with the space between said first gear, said spacer and one of said opposed portions of the toothed inner face of the belt, a first low pressure passage in said housing communicating with the space between the second gear, said spacer and said one opposed portion of the toothed inner face of the belt, a second high pressure passage in the housing communicating with the space between the second gear, said spacer and the other of said opposed portions of the toothed inner face of the belt, and a second low pressure passage in the housing communicating with the space between the first gear, said spacer and said other opposed portion of the toothed inner face of the belt.

2. A pump or fluid motor comprising spaced first and second rotary gears, a flexible endless belt extending around said gears and formed at its inner face with spaced teeth meshing with the gear teeth at the outer peripheral portions of the respective gears, a housing enclosing said gears and said belt and having portions disposed in close running fit with the ends of said gears and belt, a spacer plate disposed between the gears and surrounded by the belt, said spacer plate having arcuate end faces shaped substantially complementary to the inwardly disposed peripheral portions of the gears and extending closely adjacent thereto and providing close running fits therat for the gears, said spacer plate being formed with flat end faces extending closely adjacent the opposed courses of the toothed inner face of the belt between the gears, a first high pressure passage in the housing at one end of the inwardly disposed peripheral portion of the first gear and communicating therat with the space between said first gear, a first one of said opposed courses of the toothed inner face of the belt and said spacer plate, a first low pressure passage in the housing at said end of the inwardly disposed peripheral portion of the second gear and communicating therat with the space between said second gear, said first one of the opposed courses of the toothed inner face of the belt and said spacer plate, a second high pressure passage in the housing at the opposite end of the inwardly disposed peripheral portion of said second gear and communicating therat with the space between said second gear, the other of said opposed courses of the toothed inner face of the belt and said spacer plate, and a second low pressure passage in the housing at said opposite end of the inwardly disposed peripheral portion of said first gear and communicating therat with the space between said first gear, said other opposed course of the toothed inner face of the belt and said spacer plate.

3. A pump or fluid motor comprising four spaced rotary gears, an endless flexible belt extending around said gears and formed of a pliable material to conform to the peripheries of the gears and extend in a straight line from the periphery of one gear to the periphery of an adjacent gear, said belt being formed at its inner face with spaced teeth meshing with the teeth on each gear located at the outwardly disposed peripheral portion thereof, a housing en-

closing said gears and said belt and having portions disposed in close running fit with the ends of said gears and belt, a spacer disposed between the spaced gears, said spacer having arcuate end faces extending respectively closely adjacent the inwardly disposed peripheral portions of the gears and providing close running clearances therefor, said spacer being formed with flat end faces extending closely adjacent the toothed inner face of the belt between each pair of adjacent gears, high pressure passages in the housing at one end of each of said arcuate end faces on the spacer and communicating therat with the respective space between the corresponding gear, the toothed inner face of the belt and the spacer, and low pressure passages in the housing at the respective opposite ends of said arcuate end faces on the spacer and communicating therat with the respective space between the corresponding gear, the toothed inner face of the belt and the spacer, said high and low pressure passages being arranged in alternate sequence along the belt for the supply of fluid at alternate ones of said passages to the intertooth spaces on the gears and the belt and the discharge of fluid at the others of said passages from said intertooth spaces on the gears and the belt.

4. A pump or fluid motor comprising an even numbered plurality of gears, greater than two, an endless flexible belt extending around said gears and formed of a pliable material to conform to the peripheries of the gears and extend in a straight line from the periphery of one gear to the periphery of an adjacent gear, said belt being formed at its inner face with spaced teeth meshing with the teeth on each gear located at the outwardly disposed peripheral portion thereof, a housing enclosing said gears and said belt and having portions disposed in close running fit with the ends of said gears and belt, a spacer disposed between the spaced gears, said spacer having arcuate end faces extending respectively closely adjacent the inwardly disposed peripheral portions of the gears and providing close running clearances therefor, said spacer being formed with flat end faces extending closely adjacent the toothed inner face of the belt between each pair of adjacent gears, high pressure passages in the housing at one end of each of said arcuate end faces on the spacer and communicating therat with the respective space between the corresponding gear, the toothed inner face of the belt and the spacer, and low pressure passages in the housing at the respective opposite ends of said arcuate end faces on the spacer and communicating therat with the respective space between the corresponding gear, the toothed inner face of the belt and the spacer, said high and low pressure passages being arranged in alternate sequence along the belt for the supply of fluid at alternate ones of said passages to the intertooth spaces on the gears and the belt and the discharge of fluid at the others of said passages from said intertooth spaces on the gears and the belt.

5. A rotary pump or fluid motor comprising a pair of spaced end gears and a middle gear located therebetween in spaced relation from both end gears, an endless flexible belt extending around said gears and adapted to conform to the peripheries of the gears and extend in a straight line from the periphery of one gear to the periphery of an adjacent gear, said endless belt being formed with spaced teeth on its inner face meshing with the teeth on the end gears located at the outwardly disposed peripheral portions thereof and meshing with the teeth on the middle gear at opposite peripheral portions thereof, a housing enclosing said gears and the belt and having portions disposed in close running fit with the ends of said gears and belt, a first spacer disposed between the middle gear and a first one of said end gears, said first spacer having opposite arcuate end faces extending respectively closely adjacent the inwardly disposed peripheral portion of said first end gear and the adjacent peripheral portion of the middle gear and providing close running clearances therat for said gears, said first spacer having opposite flat end faces extending closely adjacent the toothed inner face of

the belt between said first end gear and the middle gear and providing close running clearances for the belt thereat, a second spacer disposed between the middle gear and the other end gear, said second spacer having opposite arcuate end faces extending respectively closely adjacent the inwardly disposed peripheral portion of said other end gear and the adjacent peripheral portion of the middle gear and providing close running clearances thereat for said gears, said second spacer having opposite flat end faces extending closely adjacent the toothed inner face of the belt between said other end gear and the middle gear and providing close running clearances for the belt thereat, high pressure passages in the housing at one end of each of said arcuate end faces on the spacers and communicating therewith the respective space between the corresponding gear, the toothed inner face of the belt and the corresponding spacer, and low pressure passages in the housing at the respective opposite ends of the arcuate end faces on the spacers and communicating therewith the respective space between the corresponding gear, the toothed inner face of the belt and the corresponding spacer, said high and low pressure passages being arranged in alternate sequence along the belt for the supply of fluid at alternate ones of said passages to the intertooth spaces on the gears and the belt and the discharge of fluid at the others of said passages from said intertooth spaces on the gears and the belt.

6. The device of claim 5, wherein said middle gear is larger in diameter than either of said end gears.

7. The device of claim 5, wherein said gears have their respective axis of rotation lying substantially in the same plane.

8. A fluid pump or motor comprising a plurality of spaced rotary gears separated from one another and mounted for rotation on parallel axes, said gears having gear teeth formed on the periphery thereof, an endless flexible belt passing around said gears adapted to conform to the gear peripheries and extend in a straight line from the periphery of one gear to the periphery of an adjacent gear, said belt having gear teeth extending across the inner face thereof and shaped to mesh with the teeth on the gears to be driven thereby in a closed path disposed normal to the axes of said gears, and a housing enclosing said gears and belt and having spaced high and low pressure passages therein between the gears and belt at the points of meshing engagement and disengagement of the belt with the gears, said housing having portions extending closely adjacent the toothed peripheries of the gears and the toothed inner face of the belt and also portions disposed in close running fit with the ends of the gears and belt intermediate each high and low pressure passage to form a running seal between each high and low pressure passage.

9. The combination of claim 8 wherein said high pressure passages each communicate with the outer face of the belt as well as at the toothed inner face thereof to balance the fluid pressure on the opposite faces of the belt at said high pressure passages.

10. The combination of claim 8 including means for applying fluid pressure at the outer face of the belt equal to the fluid pressure on the inner face thereof at each of the high pressure passages to balance the fluid pressure on opposite faces of the belt at said high pressure passages.

11. A fluid pump or motor comprising a plurality of spaced rotary gears separated from one another and mounted for rotation on parallel axes, said gears having gear teeth formed on the periphery thereof, an endless flexible belt passing around said gears adapted to conform to the gear peripheries and extend in a straight line from the periphery of one gear to the periphery of an adjacent gear, said belt having gear teeth extending across the inner face thereof and shaped to mesh with the teeth on the gears, to be driven thereby in a closed path disposed normal to the axes of said gears, a housing

enclosing said gears and belt and having spaced high and low pressure passages therein between the gears and belt at the points of meshing engagement and disengagement of the belt with the gears, and spacer means separating the gears and extending closely adjacent the toothed inner face of the belt between the gears and having curved faces extending closely adjacent the mutually adjacent peripheral portions of the gears, said housing having portions extending closely adjacent the end faces of the gears and belt between each of said high and low pressure passages to thereby form a running seal between each high and low pressure passages.

12. A fluid pump or motor comprising a plurality of spaced rotary gears mounted for rotation on parallel axes and each formed with a cylindrical periphery having gear teeth extending thereacross, an endless flexible belt passing around said gears and formed of a pliable material to conform to the peripheries of said gears and extend in a straight line from the periphery of one gear to the periphery of an adjacent gear, said belt having a plurality of teeth extending across the inner face thereof and shaped to mesh with the teeth on the gears to be driven thereby in a closed loop disposed normal to the axes of said gears, a housing enclosing said gears and belt and having spaced high and low pressure passages therein between the gears and the belt at the points of meshing engagement and disengagement of the belt with the gears, said housing having portions extending closely adjacent the toothed peripheries of the gears and the toothed inner face of the belt and also portions disposed in close running fit with the ends of the gears and belt and in close running fit with the outer side of the belt intermediate each high and low pressure passage to form a running seal between each pair of high and low pressure passages.

13. A fluid pump or motor comprising a plurality of spaced rotary gears formed with gear teeth on the peripheries thereof and mounted for rotation about parallel axes, an endless flexible belt passing around said gears and formed of a pliable material to conform to the gear peripheries and extend in a straight line from the periphery of one gear to the periphery of an adjacent gear, said belt having a smooth outer face and formed at its inner face with a plurality of teeth spaced apart along the length of the belt and shaped to mesh with the teeth on the gears, spacer means separating the gears and formed with arcuate faces extending closely adjacent the mutually adjacent portions of the gears and flat end faces extending closely adjacent the straight inner faces of the belt between the gears, a housing enclosing said gear, belt and spaced means and closely overlying the ends of said gears and belt and closely overlying the smooth outer periphery of said belt, said housing having high and low pressure passages therein between the periphery of the gears, the toothed inner face of the belt and said spacer means at the points of meshing engagement and disengagement of the belt with the gears, said high and low pressure passages being disposed in alternate sequence along the belt for the admission of fluid at alternate ones of said passages to the intertooth spaces on the gears and the belt and the discharge of fluid at the others of said passages from the intertooth spaces of the gears and belt.

14. A fluid pump or motor comprising a gear assembly including a plurality of spaced rotary gears formed with gear teeth on the peripheries thereof and mounted for rotation about parallel axes, an endless belt passing around said gear assembly and formed of a pliable material to conform to the peripheries of said gears and extend in a straight line therebetween, said belt having teeth formed on the inner face thereof shaped to mesh with the teeth on said gears, said belt also having teeth formed on the outer face thereof, a gear disposed outside of said belt in meshing engagement with the teeth on the outer face thereof, a housing enclosing said gears and belt and having high and low pressure passages there-

in at the points of meshing engagement and disengagement of the belt with said gears, said housing having portions disposed in close running fit with the peripheries of the gears of said assembly and with the periphery of the gear external of said belt between the points of meshing engagement and disengagement of each gear with the belt, said housing also having portions disposed in close running fit with the ends of the gears and belt between the points of meshing engagement and disengagement of the gears with said belt, and portions on said housing disposed in close running fit with the outer face of said belt between the points of meshing engagement and disengagement of the gear disposed externally of said belt.
